(57) CLAIM

The ornamental design for a cleaning device, as shown and described.

DESCRIPTION

FIG. 1 is a perspective top view of the cleaning device
shown in FIG. 1;

FIG. 2 is a perspective bottom view of the cleaning device
shown in FIG. 1.

FIG. 3 is an elevational front view of the cleaning device
shown in FIG. 1;

FIG. 4 is an elevational rear view of the cleaning device
shown in FIG. 1;

FIG. 5 is an elevational left side view of the cleaning device;
FIG. 6 is an elevational right side view of the cleaning
device;

FIG. 7 is a top view of the cleaning device of the present invention; and,

FIG. 8 is a bottom view of the cleaning device of the present invention.
